US00D907287S

(12) **United States Design Patent** (10) Patent No.: **US D907,287 S**
(45) Date of Patent: ** Jan. 5, 2021

(54) **ELECTRONIC CIGARETTE BATTERY**

(71) Applicant: **Shenzhen Senchuang Dingding technology Co. Ltd.**, Shenzhen (CN)

(72) Inventor: **Ling Wang**, Shenzhen (CN)

(**) Term: **15 Years**

(21) Appl. No.: **29/690,084**

(22) Filed: **May 6, 2019**

(51) LOC (13) Cl. **27-02**

(52) U.S. Cl.

USPC **D27/162**

(58) **Field of Classification Search**

(57) **CLAIM**

The ornamental design for an electronic cigarette battery, as shown and described.

DESCRIPTION

FIG. 1 is a first perspective view of an electronic cigarette battery showing my design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion in FIG. 1. The evenly-spaced broken lines in the drawings depict portions of the electronic cigarette battery that form no part of the claimed design. The dash-dot broken lines surrounding the enlarged view are for annotative purpose only and form no part of the claimed design.
